SUPERCHARGED FURNACE

René Andonnax, Paris, France

Application April 27, 1936, Serial No. 76,689
In France April 29, 1935

7 Claims. (Cl. 236—15)

In the case of fireboxes supercharged by means of a blower driven by a turbine utilizing the energy of gases of combustion, it is known that, for a given supply of fuel, there is only one speed of the turbo-blower unit at which parity exists between the power applied to the blower and that received by the gas turbine. This speed corresponds with a certain delivery of air, and therefore with a certain weight of air per kilogramme of fuel. It is found that this latter proportion is not the same in the case of variations in the quantity of fuel supplied. However, in order to obtain optimum conditions of combustion, it is important that the proportion of air and fuel should remain approximately constant under all running conditions. In the case of heavy oil, for example, the desired proportion is about 16 kg. of air per kilogramme of heavy oil.

In accordance with the foregoing, balance of power in the blower and turbine, in the case of this proportion of air, exists only for a given rate of combustion corresponding to a given speed of rotation of the turbo-blower.

In the case of rates of combustion higher than this condition of equilibrium, the gas temperature rises, the power of the gas turbine tends to become excessive and equilibrium is established, in the unit, for a speed corresponding with an excess of air as compared with the proportion mentioned above.

On the other hand, in the case of lower rates, the power supplied to the gas turbine decreases more rapidly than that necessary for compressing the air; so that, in order to prevent a lack of air of combustion and to restore the optimum proportion, it is necessary to provide the unit with a supply of motive power from a prime mover of some kind, such as, by way of concrete example, a steam turbine.

For a given supply of fuel, this supply of power will obviously be more extensive when it is desired to effect the combustion with a greater excess of air. It is therefore, conceivable that the control of the excess of air may be effected solely by exerting influence on the said supply of power, for example on the admission of steam when the power is supplied by a steam turbine.

It should be noted however, that, in general, this power represents only a small fraction of the total power, so that the slight variations to which it will be subjected, have only a very gradual effect on the running of the unit, the management of which will therefore be rendered difficult.

Moreover, in the case of operative conditions beyond the state of equilibrium, and in which, of

course, the said supply of power will not be provided, this method of control is lacking and, in general, the excess of air tending to occur is reduced by acting on the gases admitted into the turbine, either by diverting a portion of said gases, or by throttling the intake or exhaust of the turbine. Such arrangement leads to control members, the embodiment of which is a critical matter, by reason of the high temperature and large volume of the gases to be controlled.

Finally, in the case of boiler fireboxes, the following circumstance further increases the difficulty of control. When, starting with a controlled combustion, the excess of air is increased, whilst the fuel supply remains the same, a rise in the temperature of the gases at the delivery end of the sheaf of tubes is usually observed. This is due chiefly to the heat exchange being reduced out of proportion to the lowering of the temperature in the firebox. Consequently, if a slight disturbance of equilibrium should occur accidentally, corresponding to an increased delivery of air, followed by a rise in the temperature of the gases, the gas turbine will be supplied with more power, tend to increase in speed and therefore maintain, or even accentuate the said disturbance of equilibrium. It is conceivable that, in certain cases, a phenomenon that is unstable, within certain limits at least, may occur.

According to the present invention the control of combustion is effected by a branch located in the main air circuit, between the delivery of the blower and the intake of the gas turbine, and provided with a throttle or adjustable damper. The control obtained in this manner is far more sensitive, and prevents the above-mentioned unstable effect.

In the accompanying drawing which illustrates by way of example, an embodiment of the invention:

Figure 1 is a diagrammatic sectional elevation of a device adapted to the special case of a boiler firebox under pressure, and,

Figure 2 is a diagrammatic section of a gas turbine, showing an arrangement for cooling the rotor of said turbine.

As shown in Figure 1 a blower 1 is driven by a gas turbine 2, and by a steam turbine, or other auxiliary motor, 3. Air drawn in through an intake 4 is delivered to the combustion chamber and liquid fuel is supplied to a burner 6 through a pipe 7. After having passed through a sheaf of tubes 8 in the boiler, the gases of combustion reach the gas turbine 2, by way of a conduit 9, and leave it through a conduit 10.

The power of the auxiliary motor 3 is controlled, for each set of working conditions of the boiler, in such a manner that the blower delivers a slight excess of air, for example 10% in relation 5 to the amount that would be sufficient to burn the fuel consumed under said conditions. It should be noted that it is thus necessary to provide a larger supply of power than if the object were to supply only the amount of air strictly 10 needed for combustion, but, as a matter of fact, the compression of this excess air costs very little, since a large portion of the power thus expended is recovered in the gas turbine.

The air furnished by the blower 1 is divided 15 into two portions, the one, passing into the air distributors of the burners, ensuring the combustion and, after having traversed the boiler tubes 8—reaching the intake of the gas turbine 2, whilst the other, which passes direct to the 20 intake of the turbine 2 by way of the branch 11 mingles with the gases of combustion. A throttle or damper 12 controls that portion of the delivery which passes into the branch 11, in such a manner that the main portion, which passes into the 25 firebox, corresponds with optimum combustion.

The throttle 12 may be acted upon by hand, or by means of an automatic device ensuring, for example, the maintenance of a constant ratio between the supplies of air and heavy oil. Many 30 existing proportional control devices may be employed for this purpose, the principle of one such being represented, by way of example, in Figure 1.

Before reaching the burner 6 the liquid fuel 35 passes through a Venturi device 13, in which it undergoes a pressure drop proportional to the square of the supply. The elastic diaphragm 14 of a manometric capsule 15 is exposed to this differential pressure and another manometric 40 capsule 16—also provided with an elastic diaphragm 17—is exposed to the differential air pressure between the two points 18 and 19, the one located at the entrance to the boiler, and the other at the outlet end of the tubes 8. This pressure difference is proportional to the square of 45 the air delivery. The two diaphragms are connected by a rod 20 and are so arranged that the efforts to which they are exposed act in opposition. It will be evident that the equilibration 50 corresponds with the proportional values of the differential pressures, that is to say, of the supplies of air and fuel. The movements of the rod 20 are transmitted to the control throttle 12 through a train of levers articulated at 21, 22, 23.

If the supply of fuel is increased, the depression 55 in the venturi 13 also increases and, acting on the diaphragm 14, causes the throttle 12 to close. The supply of air passing into the combustion chamber therefore increases at once. At the 60 same time, the temperature of the gases of combustion rises. The gas turbine, which thus receives more power, speeds up progressively and the blower delivers more air. The suction between the points 18 and 19 increases and, acting 65 on the diaphragm 17, tends to reopen the throttle 12, until proportionality is restored between the new supplies of air and fuel. The conditions are reversed when the supply of fuel is reduced.

This control functions in a similar manner in 70 the case of running speeds higher than that at which the gas turbine is able to drive the blower unaided. It is known that, for these conditions, the power of the gases is more than sufficient, and the unit tends to furnish a considerable excess 75 of air by itself. The aperture of the throttle 12

adjusts itself in such a manner as always to maintain at a suitable value the quantity of air passing into the firebox, the surplus being drawn off by way of the branch 11 and serving to cool the gases at the intake of the turbine, thereby tending to lessen the power received by the latter, and, consequently, to limit its speed.

In the case of conditions approximating to the maximum speed of the unit, it is evident that the blower, which delivers a considerable excess of air, is called upon to run at a higher speed than would be necessary for supplying just enough air to burn the maximum supply of fuel. This may give rise to inconvenience if the rotor has been designed solely to stand the stresses corresponding with the maximum running conditions. In such a case it is necessary to be able to slow down the unit. All that is required for this contingency is the provision of a control member producing a pressure drop at any point in the air 10 circuit, or the gas circuit, such as a throttle located at the intake or delivery of the blower, or at the intake or exhaust of the gas turbine.

Again, a portion of the gases can be diverted from the intake 9 of the turbine to the exhaust 25 10, or preferably, a portion of the air delivered by the blower, may be diverted into the atmosphere or into the exhaust of the turbine.

For this purpose, a centrifugal governor 24 (Figure 1) of the speed limiting type, is driven by 30 the motor group. The movements of its collar 25 are transmitted, through a train of levers articulated at 26—27, to a throttle or damper 28 arranged in an air branch 29 provided on the delivery of the blower.

When the speed exceeds a given value, this 35 throttle 28 opens, thus reducing the supply of gas passing to the turbine, and consequently reducing the power of the latter and automatically lessening the speed. In the example shown in Figure 2, 40 this air branch 29 is utilized for cooling the rotor of the gas turbine.

The air from the branch 29 is distributed between the two branch pipes 30 and 31 opening into the two chambers 32 and 33 of the gas turbine communicating with the exhaust. It then cools the two sides of the rotor 34, by circulating in the spaces 35 and 36 provided between the rotor and stator of the turbine. This supply of 45 fresh air increases with the speed, and therefore 50 with the load on the boiler, a particularly advantageous circumstance in view of the fact that the gases are then at their highest temperature.

What I claim is:

1. A system including a supercharged furnace 55 which comprises, in combination, means for feeding liquid fuel to said furnace, a blower arranged to feed air to said furnace, means, including a gas turbine, for driving said blower, means for feeding the combustion gases from said furnace 60 as motive fluid to the intake of said gas turbine, adjustable means for feeding a variable portion of the air delivered by said blower directly to the intake of said turbine, and means responsive to variations in the ratio of the rates of feed of said 65 fuel and said air, respectively, to said furnace for controlling said adjustable means.

2. A system including a supercharged furnace 70 which comprises, in combination, means, including a conduit for feeding liquid fuel to said furnace, a blower arranged to feed air to said furnace, means, including a gas turbine, for driving said blower, means for feeding the combustion gases from said furnace as motive fluid to the intake of said gas turbine, a venturi inserted in 75

series in said conduit, a passage connecting the outlet of said blower directly to the intake of said gas turbine, regulating means for controlling the flow of air through said passage, and means, operative by the combined actions of the suction produced by said venturi in said conduit and of the difference between the pressure of the air discharged from said blower and the pressure of the gases fed to said turbine, for controlling said regulating means.

3. A system including a supercharged furnace which comprises, in combination, means, including a conduit for feeding liquid fuel to said furnace, a blower arranged to feed air to said furnace, means, including a gas turbine, for driving said blower, means for feeding the combustion gases from said furnace as motive fluid to the intake of said gas turbine, a venturi inserted in series in said conduit, a conduit connecting the outlet of said blower directly to the intake of said gas turbine, regulating means for controlling the flow of air through said last mentioned conduit, a manometric capsule, a diaphragm in said capsule, means for connecting the portion of said capsule located on one side of said diaphragm with the part of said first mentioned conduit located before said venturi, means for connecting the portion of said capsule located on the other side of said diaphragm with said venturi, another manometric capsule, a diaphragm forming a partition in said second capsule, means for connecting the portion of said second capsule located on one side of said last mentioned diaphragm with the outlet of said blower, means for connecting the portion of said second mentioned capsule located on the other side of said last mentioned diaphragm with the intake of said turbine, and means, operative by both of said diaphragms, for controlling said regulating means.

4. A system including, in combination, a supercharged furnace, means for feeding liquid fuel to said furnace, a blower arranged to feed air to said furnace, means, including a gas turbine, for driving said blower, means for feeding the combustion gases from said furnace as motive fluid to the intake of said gas turbine, a conduit connecting the outlet of said blower directly to the intake of said turbine, regulating means for controlling the flow of air through said conduit, means for causing a variable portion of the air delivered by said blower to escape into the atmosphere, and a governor, operative by said blower, for operating the last mentioned means when the speed of rotation of the blower exceeds a given value.

5. A system including a supercharged furnace which comprises, in combination, means for

feeding a non-solid fuel to said furnace, a blower arranged to feed air to said furnace, means, including a gas turbine, for driving said blower, means for feeding the combustion gases from said furnace as motive fluid to the intake of said gas turbine, adjustable means for feeding a variable portion of the air delivered by said blower directly to the intake of said turbine, and means, responsive to variations in the ratio of the rates of feed of said fuel and said air, respectively, to said furnace, for controlling said adjustable means.

6. A system including a supercharged furnace which comprises, in combination, means for feeding liquid fuel to said furnace, a blower arranged to feed air to said furnace, means, including a gas turbine, for driving said blower, means for feeding the combustion gases from said furnace as motive fluid to the intake of said gas turbine, a conduit connecting the outlet of said blower directly to the intake of said turbine, regulating means for controlling the flow of air through said conduit, and means, responsive to variations in the ratio of the rates of feed of said fuel and said air, respectively, to said furnace, for controlling said regulating means.

7. A system including a supercharged furnace which comprises, in combination, means, including a conduit, for feeding liquid fuel to said furnace, a blower arranged to feed air to said furnace, means, including a gas turbine, for driving said blower, means for feeding the combustion gases from said furnace as motive fluid to the intake of said gas turbine, a venturi inserted in series in said conduit, a passage connecting the outlet of said blower directly with the intake of said turbine, regulating means for controlling the flow of air through said conduit, a manometric capsule, a diaphragm in said capsule, means for connecting the portion of said capsule located on one side of said diaphragm with the part of said conduit located before said venturi, means for connecting the portion of said capsule located on the other side of said diaphragm with said venturi, another manometric capsule, a diaphragm forming a partition in said second mentioned capsule, means for connecting the portion of said second mentioned capsule located on one side of said last mentioned diaphragm with the outlet of said blower, means for connecting the portion of said second mentioned capsule located on the other side of said last mentioned diaphragm with the intake of said turbine, a rod interconnecting said two diaphragms, and means operatively connected with said rod for controlling said regulating means.
